UNITED STATES PATENT OFFICE

WILLIAM D. FERRIS, OF STERLING, ILLINOIS, ASSIGNOR TO HUSTLER TOY CORPORATION, OF STERLING, ILLINOIS, A CORPORATION OF ILLINOIS

STRUCTURAL TOY

Application filed January 25, 1930. Serial No. 423,365.

This invention relates to structural toys, and more particularly to those involving rods or dowels, together with members for connecting the rods or dowels together in various shapes and forms, thereby to permit the building of toy structures of different kinds.

Generally stated, the object of the invention is to provide a novel and improved construction and arrangement whereby rods or dowels having solid or nonyielding end portions can be used, in combination with connecting members having yielding or resilient sockets for the ends of said rods or dowels, thereby to connect the rods or dowels in different ways, to form toy structures of different kinds.

It is also an object to provide certain details and features of construction and combinations tending to increase the general efficiency and the desirability of a set of structural toy parts of this particular character.

To the foregoing and other useful ends, the invention consists in matters hereinafter set forth and claimed and shown in the accompanying drawings, in which—

Fig. 1 is a side elevation of a combination of rods or dowels and connecting members therefor, embodying the principles of the invention;

Fig. 2 is an enlarged detail section on line 2—2 in Fig. 1; and

Fig. 3 is a similar section on line 3—3 in Fig. 1.

As thus illustrated, the invention comprises a plurality of dowels or rods, preferably of wood, such as the rods or dowels 1, 2 and 3, shown in the drawings. These rods or dowels are solid and have nonyielding end portions.

A plurality of connecting members are provided, for connecting the said rods or dowels in different ways, to form toy structures of different kinds. Each connecting member comprises two sheet metal sections or halves 4 and 5, which are stamped out of sheet metal and formed in the desired manner. The section 5 is provided with lugs 6 that are bent over the edges of the section 4 to hold the two halves together. The section 4 is provided with radial portions 7, and the section

5 is provided with similar radial portions 8, the portions 7 and 8 forming resilient split sockets for the solid or nonyielding end portions of the said rods or dowels. The hub portion of each connecting member is provided with a split cylinder 9 inserted therein, which cylinder is expandable and resilient to receive a rod or dowel, and to frictionally hold the same, when such is necessary or desirable in the building of any structural toy.

In use, the rods or dowels 1, 2 and 3, or similar elements, are inserted in the resilient clamping sockets formed by the portions 7 and 8, previously mentioned. With rods and dowels of different lengths and sufficient number, and with sheet metal connecting members of the kind shown and described, various toy structures can be built in a manner that will be readily understood. The sockets of the connecting members are flexible and resilient, to frictionally hold the ends of the rods or dowels, and hence the ends of the rods or dowels may be solid and nonyielding in character.

What I claim as my invention is:

1. In a structural toy, the combination of rods or dowels having nonyielding smooth and rigid end portions, and sheet metal connecting members having flexible and resilient sockets for the frictional retention of the end portions of said rods or dowels, each socket having an individual closed sheet metal bottom limiting the insertion of the rod or dowel, said bottom being spaced apart, preventing engagement of the rods with each other, whereby to connect the rods or dowels in different ways to form structural toys of different forms, said connecting members each comprising sheet metal halves secured together, said halves having outer meeting edges between said sockets, each section provided with radial portions extending outwardly a distance beyond said edges, the radial portions of one section being opposite the radial portions of the other section, thereby providing holders forming said resilient sockets, the sides and bottom of each holder being split in the plane of said edges, together with central hub means, said halves

having annular meeting portions between said hub means and the bottoms of said sockets.

2. In a structural toy, the combination of rods or dowels having non-yielding smooth and rigid end portions, and sheet metal connecting members having flexible and resilient sockets for the frictional retention of the end portions of said rods or dowels, each socket having an individual closed sheet metal bottom limiting the insertion of the rod or dowel, said bottom being spaced apart, preventing engagement of the rods with each other, whereby to connect the rods or dowels in different ways to form structural toys of different forms, said connecting members each having a split cylinder hub forming a flexible or resilient holder for a rod or dowel, said hub having its sides spaced a distance from the closed bottom of said sockets, the ends of said hub being flanged outside at its ends to hold it against endwise displacement and to facilitate the insertion of the rod or dowel.
3. In a structural toy, the combination of rods or dowels having non-yielding smooth and rigid end portions, and sheet metal connecting members having flexible and resilient sockets for the frictional retention of the end portions of said rods or dowels, each socket having an individual closed sheet metal bottom limiting the insertion of the rod or dowel, said bottom being spaced apart, preventing engagement of the rods with each other, whereby to connect the rods or dowels in different ways to form structural toys of different forms, each connecting member comprising sheet metal halves forming sections, each section having a ring-like portion between the center of said member and the bottoms of said sockets, one section having peripheral lugs on a plurality of its outer edges, bent over the periphery of the other section, thereby holding the ring-like portions of the two sections flatwise together, said sockets extending radially from said center beyond the peripheries of the two sections.

Specification signed this 18th day of January, 1930.

WILLIAM D. FERRIS.
